CLAIM

We claim the ornamental design for an actuator strap cap, as shown and described.

DESCRIPTION

FIG. 1 is a perspective view of the strap cap showing our new design;

FIG. 2 is a side view thereof;

FIG. 3 is a top view thereof;

FIG. 4 is another side view thereof;

FIG. 5 is a bottom view thereof;

FIG. 6 is an end view thereof; and,

FIG. 7 is another end view thereof.
